US00D742867S

(12) **United States Design Patent**
Lee et al.

(10) **Patent No.:** US D742,867 S
(45) **Date of Patent:** ** Nov. 10, 2015

(54) **MOBILE PHONE**

(71) Applicant: **LG ELECTRONICS INC.**, Seoul (KR)

(72) Inventors: **Hophil Lee**, Anyang-si (KR);
Seunghwan Song, Namyangju-si (KR);
Seungbeom Park, Bucheon-si (KR)

(73) Assignee: **LG Electronics Inc.**, Seoul (KR)

(**) Term: **14 Years**

(21) Appl. No.: **29/476,214**

(22) Filed: **Dec. 12, 2013**

(30) **Foreign Application Priority Data**

Jun. 14, 2013 (KR) 30-2013-0030884
(51) **LOC (10) Cl.** **14-03**

(52) **U.S. Cl.**

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image; and,

FIG. 6 is a rear perspective view thereof.

The broken lines shown in the figures show non-claimed portions of the mobile phone. The broken lines form no part of the claimed design.

1 Claim, 6 Drawing Sheets
